UNITED STATES PATENT OFFICE.

NOEL STATHAM, OF IRVINGTON, NEW YORK.

SAFETY RAZOR.

Application filed December 19, 1919, Serial No. 346,132. Renewed April 30, 1923.

To all whom it may concern:

Be it known that I, NOEL STATHAM, a subject of the King of Great Britain, and resident of Irvington, county of Westchester, State of New York, have made a certain new and useful Invention Relating to Safety Razors, of which the following is a specification, taken in connection with the accompanying drawing.

10 This invention relates especially to razors which may be of the safety razor type and with which stropping devices may be combined so that the razor blade may be stropped without disengaging it from the blade holder and cooperating handle which support it in shaving position. The handle which preferably comprises a resilient handle extension which may advantageously be formed of resilient sheet metal 20 may have its lower or gripping portion reinforced in suitable ways. The handle may have pivoted thereto adjacent the extension portion thereof a hinge support carrying a hinge pin or device cooperating with the handle extension and at some distance from the pivot so that this hinge may be swung around the end of the handle into any desired position. The blade holder which may hold or engage the razor blade in any suitable way may be connected to the hinge pin so that it can fold either out into angularly projecting shaving position or down into substantially the plane of the handle when desired. In this way the razor blade with 30 which a guard may be connected or associated in any desired way is foldably and swingingly connected to the handle and suitable cam devices may be arranged between the blade holder and the handle extension, for instance, to yieldably support the blade holder and blade in its projecting shaving position while allowing it to be pushed down into flat or carrying position without the necessity of releasing any special latching devices or complicated detents. For stropping, the blade holder may be folded into substantially the plane of the handle and then if desired swung around the handle pivot so that that edge of the 40 blade projects somewhat beyond one edge of the handle in which position it may be retained by any suitable or gripping retaining devices, and if desired these devices may comprise a wedging tongue or other disengaging member to separate the guard and blade holder when the parts are

swung into stropping position, so that under these conditions the guard may, if desired, be swung over to the other side of the handle so as to be out of the way and not interfere with the stropping of the blade. Of course any suitable razor blade may be used in such a holder of resilient sheet metal so as to grip the razor blade and sufficiently tightly hold it in position while still allowing the withdrawal thereof when a new blade is desired.

In the accompanying drawing showing in a somewhat diagrammatic way various illustrative embodiments of this invention,

Fig. 1 is a perspective view showing an illustrative razor in shaving position.

Fig. 2 is a corresponding enlarged longitudinal section.

Fig. 3 is a side view corresponding to Fig. 2.

Fig. 4 is an elevation showing the razor on substantially the same scale as Fig. 1 with the blade holder and cooperating parts folded up substantially into line with the handle.

Fig. 5 is a corresponding elevation showing the blade holder swung around to bring it into stropping position.

Fig. 6 is a corresponding view with the guard swung away toward the other side of the handle.

Fig. 7 is an enlarged transverse sectional view taken substantially along the line 7—7 of Fig. 6.

Fig. 8 is a perspective view showing another form of holding device to hold the guard in position with respect to the razor blade; and

Fig. 9 is a longitudinal section showing another form of razor.

In the illustrative embodiment of the invention shown in Figs. 1 to 3, the razor handle which may in many cases be advantageously formed of sheet metal may have a resilient handle extension such as 19 and an adjacent pivot such as the rivet 16 which may connect to the handle a swinging hinge support or plate 14 which may swing around this pivot 16 in the plane of the handle and if desired be provided with a separate hinge pin such as 5 cooperating with the resilient handle extension. It is desirable to reinforce the other end of the handle and for this purpose the handle may be made of double thickness sheet metal at least throughout part of the same, so that

the back plate or portion 18 may be stiffened by another front plate or portion 17 secured thereto at the gripping or lower end of the handle as by a pin 24 to make this part of 5 the handle which is grasped by the operator sufficiently rigid for the desired purpose, and in some cases it may also be formed with roughened or corrugated surfaces or edges, as indicated to prevent slipping. The handle 10 front may advantageously be formed with a pivot tongue, such as 28, shown in Figs. 2 and 4 as forming a relatively narrow extension of the handle front through which the pivot 16 may extend and preferably formed 15 with one or more aligning edge portions, such as 22, to align the blade holder and blade for stropping purposes.

The blade and cooperating blade holder which may be of any suitable types may 20 advantageously be connected to the handle by being pivotally connected to the hinge support as by making the blade holder of one piece of resilient sheet metal such as 25 spring brass of such size and shape that the adjacent parts 2 may resiliently grip and hold the razor blade 6, while, if desired, an integral hinge tongue 3 may be formed or stamped out of this same sheet of material and brought down around the hinge pin 5 30 so as to form a secure and reliable hinge connection between these parts. In this way, also a corresponding recess 47 may be formed in the under side of the blade holder, as is shown in Fig. 6, which may extend toward 35 but preferably not to the outer edge of the blade holder to facilitate insertion of the blade 6 which may be provided with projecting ears or aligning portions 25 cooperating with corresponding recesses 49 in the 40 blade holder to promote longitudinal alignment between the parts. If desired, also a metallic facing or plate 1 may be soldered or otherwise secured to the outer side of the blade holder to give a somewhat more finished appearance thereto and to cooperate 45 with the handle extension when the blade holder is swung up into the flat extended position shown in Fig. 4, for instance, although this facing is not necessary in all 50 cases.

Any desired form of holding or detent or retaining devices may be used preferably to retain the blade holder and blade in self-supporting shaving position projecting at a 55 substantial angle to the handle and for this purpose it is advantageous to use cam devices on the cooperating portions or faces of the blade holder and handle or handle extension so that when the blade holder is 60 swung up into some such angularly projecting position as shown in Figs. 1 and 2 it may be yieldingly retained in that position and held securely enough for shaving purposes. By forming one or more cam devices 65 on the pivotal or hinge portions of the blade

holder, such as 4, the relatively flat or retaining portions or faces of these cam members may engage with the resilient handle extension which presses against them strongly enough to hold the blade holder 70 and connected blade in this projecting shaving position with considerable firmness so as to require at least a number of pounds pressure before they fold or move out of this position while at the same time they are 75 yieldingly held so that there are no positive interlocking detents or similar parts which must be manually operated or unlatched before the projecting razor blade and blade holder are swung down against the handle 80 or up into line therewith, as shown in Fig. 4. When in this extended position shown in Fig. 4 the facing 1 is swung into engagement with the resilient handle extension and has a retaining or cam action in connection therewith while the cam devices 4 on the blade holder which are preferably located sufficiently far from the pivot 16 when this pivot is secured to the handle back which forms the 85 resilient handle extension so as to give the 90 desired resilient action of these parts and these cam devices may be formed with a face or projection adapted to yieldingly hold the parts in folded position when the blade holder is pushed down from the shaving position shown in Figs. 1 and 2 into substantially the plane of the handle after which, if desired, it may be swung about the pivot 16 so that the blade may be longitudinally 95 arranged with respect to the handle so that the folded razor occupies still less room in this carrying position. It is of course understood that when the blade holder and blade are in their angularly extended shaving position shown in Figs. 1 and 2 they may be swung laterally about the pivot 16 so that the razor edge may assume any desired inclined position for shaving purposes.

It is advantageous in many cases to have a guard arranged in connection with the razor blade and any suitable type of guard may be used properly cooperating with the razor edge and preferably permanently connected to the blade holder or handle so as to prevent the loss of any of these parts in service. 110 For this purpose it is advantageous in many cases to pivot the guard such as 7 to the hinge pin 5 and as indicated in Fig. 6 this guard may have one or more hinge portions, such as 23, arranged in cooperation with the hinge pin 5 so that the guard may move about this hinge pin either together with the blade holder and blade or separately therefrom when the parts are swung outward 115 into separated stropping position as shown in Fig. 6. It is desirable to connect the guard to the blade holder when the parts are in shaving position and a yieldable connecting device or clip such as 48 may be formed on one or both sides of the guard so 120 125 130

as to snap over the corresponding side of the blade holder and securely hold the parts in this shaving position in which they both have hinge movement in folding about the 5 hinge pin 5 as above indicated. The guard may of course be formed with a curved lip or edge 12 adjacent the edge of the blade and with a series of grooves and depressions 10 as well as with one or more recesses or 15 cutaway portions 13 as shown in Figs. 2 and 6 to promote cleaning and allow the escape of lather, etc. It is not, however, necessary to have the laterally connecting clips 48 to hold these parts together, since, if desired, 20 the guard may be provided either instead of or in connection with these clips with cam devices, such as 9, adjacent its end portions, for instance, so that the relatively flat or holding parts of these cam portions may engage with the handle or blade holder portions to yieldingly hold the guard in desired position with respect to the blade. As indicated in Figs. 2 and 3 these cams 9 may engage the facing plate 1 on the blade holder, 25 for example, so as to firmly but yieldingly retain these parts in such cooperative position. This arrangement thus yieldingly holds the guard and blade together during 30 shaving and allows the guard to be swung away from the blade for cleaning and stropping, if desired. For stropping it is desirable to have the edge of the razor blade project from the handle and preferably be arranged substantially parallel to the axis or 35 side of the handle, and for this purpose the blade holder and blade may be yieldably held in this stropping position by any suitable gripping or retaining device, such, for instance, as the recess 21 in the one or both 40 sides of the handle which may be formed by separating its adjacent parts or plates, as is shown in Fig. 1. This forms a recess which grippingly engages the blade holder when it is swung into the same so as to prevent accidental withdrawal until the parts are 45 swung out of this stropping position about the pivot 16. It is also desirable to automatically disengage the guard from the 50 blade holder when the parts are swung into this stropping position and for this purpose it is advantageous to form a disengaging member on the handle or adjacent parts such as the wedging tongue 20 which may wedge itself between the guard and blade holder 55 when these parts are swung about the pivot 16 down into the position shown in Fig. 5 and this forces the guard away from the blade to a considerable extent and releases any connecting clips or devices, such as 48, 60 which may be used to normally hold these parts together, thus facilitating the swinging of the guard 7 over into its disengaged stropping position shown in Figs. 6 and 7. It may be held in this stropping position by 65 the faces 10 on the cam members 9, which may engage the facing plate 1 as indicated in Fig. 7, and also if desired the guard may be formed with more or less separated holding tongues 26 which may resiliently or yieldingly engage the edges of the cam members 4 so that when the guard is forced down toward the opposite side of the handle into this stropping position as shown in Fig. 6 it is yieldingly or resiliently retained 70 therein during the stropping operation when the razor edge is drawn over a razor strop of any desired or ordinary character. Thereafter the guard may be folded over toward the blade holder and then these parts may be swung about the pivot 16 until the blade holder is free from the disengaging member 20 when the guard may be forced into close engagement with the blade holder after which these parts may be folded over against the handle so that they both assume some 75 such carrying position as the guard 7 in Fig. 6. This makes a very compact razor which will fit within an extremely small pocket carrying case, if desired. After being swung up into the extended position shown 80 in Fig. 4 the blade holder and guard may be folded downward into shaving position as shown in Figs. 1, 2 and 3.

Fig. 8 shows another form of device for holding the guard in desired position in co-operation with the blade holder and blade during shaving and this holding device comprises a resilient detent such as the spring wire 32 which may extend through a recessed edge portion or support 31 on the 85 edge of the guard 30. This wire may be bent adjacent its central portion or may fit sufficiently tightly within this recessed support so that its bent ends 34 are resiliently held against the ends of the blade support as shown in full lines in Fig. 8, or in the released position as shown in dotted lines when these ends 34 project out substantially in line with the guard out of contact with the blade holder, thus allowing the guard to be 90 swung away from the blade holder, if desired.

Fig. 9 shows another arrangement in which the handle may be formed of a double thickness pivotal portion 35, 36 through which 95 extends the pivot 38 connecting to the handle the hinge support or plate 37 having the hinge pin 39 to which the blade holder 40 of resilient material may be pivotally connected. The guard which cooperates with 100 the blade holder may in this case be removable therefrom and the guard may have the curved edge 42 cooperating with the edge of the razor while the side portions 50 connect the two substantially parallel guard plates 41 which may be slipped on either side of the blade holder and retained in that position in any suitable way as by the yielding holding springs 44 diagrammatically indicated within the guard. The guard may 105

as indicated be formed with a projecting gager on said handle adjacent said retaining resilient locking device, such as 45, which device to disengage said blade holder and may snap over the end of the handle extension 46 to firmly or positively lock the parts guard as the said blade holder swings into 70 stropping position.

6 in this shaving position in which the blade holder and blade are thus supported in projecting position extending at an angle from the handle, it being of course understood that by giving the locking device a suitable 10 angle such as indicated in Fig. 9, a yielding holding action may be secured in this way so that merely forcing down the guard or blade holder releases this locking device when the handle suspension is sufficiently 15 resilient when the pressure rises to a point considerably more than would be exerted under shaving conditions. Of course if thought necessary or desirable the locking device may be brought down further around 20 the handle extension in which case it may be manually pushed up or released before folding down the blade holder toward the handle.

This invention has been described in connection with a number of illustrative embodiments, parts, proportions, materials, devices, arrangements and methods of manufacture and use, to the details of which disclosure the invention is not of course to be limited, since what is claimed as new 30 and what is desired to be secured by Letters Patent is set forth in the appended claims.

1. In safety razors and stroppers, a metal handle having a double thickness pivotal portion, a gripping retaining device cooperating with said pivotal portion, a hinge support pivoted between the double thickness portions of said handle, a gripping 40 blade holder hinged to said hinge support, a guard pivoted to said blade holder and cam devices on said blade holder and guard to yieldably hold them in close cooperation and retain them in self supporting shaving 45 position at a substantial angle to said handle and allow their being folded into substantially the plane of said handle and a disengaging projection on said handle adjacent said retaining device to wedge between and disengage said blade holder and guard as the said blade holder swings into 50 stropping position with the blade edge substantially parallel to said handle.

2. In safety razors and stroppers, a metal handle, a gripping retaining device cooperating with said pivotal portion, a hinge support pivoted to said handle, a blade holder hinged to said hinge support, a guard pivoted to said blade holder and cam devices 60 on said blade holder and guard to yieldably hold them in close cooperation and retain them in self supporting shaving position at a substantial angle to said handle and allow their being folded into substantially the plane of said handle and a diseng-

70 3. In safety razors and stroppers, a handle, a hinge support pivoted to said handle, a blade holder pivotally connected to said hinge support, a pivotally mounted guard and cam devices on said blade holder and guard to yieldably hold them in close cooperation and retain them in self supporting shaving position at a substantial angle to said handle and allow their being folded into substantially the plane of said handle and a disengaging means to disengage 75 said blade holder and guard.

4. In safety razors and stroppers, a handle, a hinge support connected to said handle, a blade holder pivotally connected to said hinge support, a pivotally mounted guard and cam devices on said blade holder and guard to yieldably hold them in cooperation and retain them in self supporting 80 shaving position at a substantial angle to said handle and disengaging means to disengage 85 said blade holder and guard.

5. In safety razors and stroppers, a handle, a hinge support connected to said handle, a blade holder pivotally connected to said hinge support, a pivotally mounted guard and cam devices on said blade holder and guard to yieldably hold them in self supporting 90 shaving position at a substantial angle to said handle.

6. In safety razors and stroppers, a flat sheet metal handle, a retaining device cooperating with said pivotal portion, a hinge support pivoted to said handle, a blade holder pivotally connected to said hinge support, a guard connected to said blade holder and cam devices to yieldably hold said blade holder in self supporting shaving position at a substantial angle to said handle and a disengaging projection on said handle adjacent said retaining device to wedge between and disengage said blade holder and guard as the said blade holder swings toward a position with the blade edge substantially parallel to said handle.

7. In safety razors and stroppers, a handle, a support pivoted to said handle, a blade holder pivotally connected to said hinge support, a guard connected to said blade holder and devices to hold said blade holder in self supporting shaving position and a disengaging projection on said handle to disengage said blade holder and guard.

8. In razors, a flat sheet metal handle, a blade holder foldably and swingingly connected to said handle and adapted to receive a razor blade and cam retaining devices on said blade holder and cooperating with said handle to yieldably hold said blade holder in self supporting shaving position at a substantial angle to said handle.

9. In razors, a handle, a blade holder foldably and swingingly connected to said handle and adapted to receive a razor blade and cam retaining devices on said blade holder to yieldably hold said blade holder in self supporting shaving position at a substantial angle to said handle.
10. In razors, a handle, a blade holder foldably connected to said handle and adapted to receive a razor blade and cam retaining devices adjacent its folding connection with said handle to yieldably hold said blade holder in self supporting shaving position at a substantial angle to said handle.
15. 11. In safety razors, and stroppers, a resilient metal handle, a blade holder foldably and swingingly connected to said handle and adapted to receive a razor blade and retaining devices comprising a cam on said blade holder and cooperating with said handle to releasably hold said blade holder in self supporting shaving position at a substantial angle to said handle and in stropping position substantially in the plane of said handle.
20. 12. In safety razors and stroppers, a handle, a blade holder foldably and swingingly connected to said handle and adapted to receive a razor blade and retaining devices comprising a cam to releasably hold said blade holder in self supporting shaving position at a substantial angle to said handle.
25. 13. In safety razors and stroppers, a flat sheet metal handle, a blade holder foldably and pivotally connected to said handle and adapted to hold a razor blade and cam retaining devices and cooperating resilient members on said blade holder and cooperating handle to yieldably hold said blade holder in self supporting shaving position folded out at a substantial angle to said handle.
30. 14. In safety razors, and stroppers, a handle, a blade holder foldably connected to said handle and adapted to hold a razor blade and a cam retaining device and cooperating member on said blade holder and cooperating handle to yieldably hold said blade holder in self supporting shaving po-
- sition folded out at a substantial angle to 50 said handle.
15. In safety razors, a metal handle having a pivot and a flat resilient handle extension beyond said pivot, a gripping retaining device adjacent said pivot, a sheet 55 metal hinge support secured to said pivot and having a hinge at a considerable distance from said pivot and cooperating with said handle extension, a gripping blade holder and a guard pivotally connected to 60 said hinge, and cam devices on said blade holder cooperating with said handle extension and on said guard to yieldably hold them in close cooperation and retain the same in self supporting shaving position at 65 a substantial angle to said handle and allow their being swung about said pivot and folded into substantially the plane of said handle.
16. In safety razors, a metal handle having a pivot and a resilient handle extension beyond said pivot, a hinge support secured to said pivot and having a hinge at a considerable distance from said pivot and cooperating with said handle extension, a 70 gripping blade holder and a guard pivotally connected to said hinge and cam devices on said blade holder cooperating with said handle extension to yieldably retain the same in self supporting shaving position at 75 a substantial angle to said handle and allow their being swung about said pivot and folded into substantially the plane of said handle.
17. In safety razors, a metal handle having a pivot and a resilient handle extension beyond said pivot, a hinge support secured to said pivot and having a hinge at a considerable distance from said pivot and cooperating with said handle extension, a 80 gripping blade holder pivotally connected to said hinge and cam devices on said blade holder cooperating with said handle extension to yieldably retain the same in self supporting shaving position at a substantial angle to 85 said handle.

NOEL STATHAM.
